UNITED STATES PATENT OFFICE

2,478,673

SWING

Robert E. Soderholm, Worthington, Minn.

Application June 9, 1947, Serial No. 753,480

1 Claim. (Cl. 155—65.)

This invention relates generally to swings, and more particularly to a swing adapted for suspension from an overhead support, and comprising a pair of suspending cables and a seat member pivotally secured to a back rest and a unitary handle bar and pedal bar member, the device being adapted for self-propulsion, that is, propulsion by a person seated on said seat, the invention including special means for securing the cable to the overhead structure and other improvements.

It is well understood that swings adapted to be propelled by persons seated thereon have been developed and used and a patent covering the basic structure of such devices is not hereby sought, but what is sought to be protected by Letters Patent includes the hereinafter described improvements and refinements of such structure, whereby such devices are adapted to better perform the functions required thereof and whereby the structure is generally simplified.

A primary object of this invention is to provide a swing which may be easily and enjoyably operated by a person seated thereon.

It is another object of this invention to provide a swing of this character which will be very safe to operate, there being no sharp edges, hooks or other devices liable to cause injury to the user of the swing, the pedal bar being of loop character to lessen the danger of the foot sliding therefrom while the device is being operated, this feature being important inasmuch as it has been found that when a child's foot inadvertently slides from the foot pedal in such devices, the child is unbalanced and may fall from the seat of the swing.

It is another object of this invention to provide improved means for attaching the seat and the operating means to the other units of the swing.

And a last object to be specifically mentioned is to provide a device of this character which is relatively inexpensive and practicable to manufacture, and which will give generally efficient and durable service.

With these and other objects definitely in view, this invention resides in certain novel features of construction, combination and arrangement of parts and portions as will be described herein-after in detail and particularly set forth in the appended claim, reference being had to the accompanying drawings which form a material part of this application, and in which:

Figure 1 is a side elevational view of the assembled swing, shown supported on overhead struc-

ture, the cables being broken and shortened to conserve space;

Figure 2 is a front elevational view of the structure shown in Figure 1;

Figure 3 is a fragmentary rear elevational view of a portion of the device;

Figure 4 is a side elevational view of a modified form of this invention;

Figure 5 is a front elevational view of this modified form;

Figure 6 is a fragmentary elevational view of a portion of the modified form; and

Figure 7 is a plan view, taken on the line 7—7 in Figure 4 and representing the seat structure and contiguous portions, suitable for use with both illustrated embodiments of this invention.

Similar characters of reference designate similar or identical parts and portions throughout the specification and throughout the several views of the drawings.

Referring now to the drawings in detail, it will be noted that this swing is designed for attachment to overhead structure 10, by means of eye members 12, or other suitable attaching units of light character. These eye members may be secured in pairs, as illustrated in Figure 2, in spaced relation, to support clevis members 14 having terminal eyes 16 securable in the eye members 12, and adapted to be secured to and to support the upper ends of the cables 18.

The lower ends of these cables 18 are secured to eye members 20 and 22 on the upper ends of the back rest 24 and the unitary member 26, respectively. This back rest 24, as represented in Figures 1 and 3 may be of very simple character and comprise a single length of rod, preferably curved as at 28, and pivotally secured to the seat-supporting bar members 30, adjacent the rear ends thereof, by transversely disposed cross members or pins 32, associated with an eye 34 formed on the lower end of the back rest 24. These seat-supporting bars 30 will ordinarily be of tubular material and are in spaced parallel relation with the cross member or pin 32 integrally secured thereto, and a second pin 36 is similarly secured adjacent the front ends of the bars 30, so that a solid structure is provided for the support of a seat member 38. Since this invention is primarily designed for construction of metal, this seat member 38 will ordinarily be welded to the bars 30, intermediate the ends thereof, and the seat may be formed with beveled corners as in Figure 7, or otherwise formed according to individual preference.

It should be carefully noted that the pins 32

and 36 are adapted to be inserted through and to coact with sleeve members 40 and 42 secured to the eye members 34 and to the web portion 44 of the unitary member 26, respectively. These sleeve members provide better bearing support for the seat and tend to prevent undue looseness or rocking thereof during the operation of the swing.

The unitary member 26 is comprised of the said web portion 44, an upper loop comprising a handle bar 46, and a pedal bar 48 which is also of loop formation, both loops being flattened horizontally, as illustrated in the drawings. As described above the sleeve 42 is integrally secured to web portion 44 and the pin 36 inserted through this sleeve supports the front ends of the bars 30 on the said unitary member, the connection being of a pivotal character allowing the rocking or oscillation of the unitary member by hand and foot action. The upper end of the unitary member 26, that is, the flat upper portion 50 of the handle bar 46 is provided with a sleeve 52 having the eye member 22 integrally secured thereon.

It is preferred that a figure, such as a horse head 54, fashioned from sheet material, should be secured to the unitary member 26, the device being readily insertable between the two portions of the web 44, and will ordinarily be welded in place.

The modified form of this invention illustrated in Figures 4, 5 and 6 includes a clevis 56, of U-shaped form, having in-turned terminals 58 pivotally secured in the ends of a sleeve member 60, which sleeve member is formed by rolling the end of a plate 62, and this plate 62 is secured to the supporting structure 10 by any suitable means such as screws or bolts 64. This modified form of the invention, contemplates using a cable 18 similar to the cable 18 used as described above, secured to a unitary member 26 constructed according to the above description and another 18 is secured to a back rest 66 of a structure slightly different from the structure of the back rest 24. The back rest 66 comprises a loop of bar material with the lower ends thereof integrally secured to a sleeve 40, similar to that already described, this structure providing for slightly improved rigidity of connection between the back rest and the sleeve.

If preferred, the unitary member 26 may be altered as indicated in Figure 5, wherein the web 44 is simplified to comprise a single length of tubular material 68 and the handle bar 70 and the pedal bar 72 are formed by simply looping the ends of this single web portion 68. It is preferred that the ends of the handle bar and pedal bar be welded to the ends of the web portion 68, as indicated at 74, thus providing for stronger structure and eliminating the possibility of injury to the hands or ankles of the person using the swing. The operation of this invention will be clearly understood from a consideration from the foregoing description of the mechanical details thereof, taken in connection with the above recitation of the ob-

jects sought to be achieved thereby but, in recapitulation it may be noted that a person using the swing will seat himself on the seat 38 and by placing his feet in the pedal bar loop 48, grasping the handle bar 46 and rocking the unitary member 26, will be able to propel himself without the aid of an accomplice. The theory of such propulsion need not be carefully detailed here, it being only necessary to point out that the center of gravity of the swing and the person seated thereon is shifted when the unitary member 26 is moved. As a result, if this rocking motion of the unitary member is made of periodic character, a series of impulses will be imparted to the swing and oscillatory motion of considerable amplitude may be accomplished. Suspension of the swing from a plurality of points enables the operator to control the movement of the swing more carefully and to decrease the tendency of the swing to circle or to become erratic in movement. Another advantage, arising from the looped handle bar 46 construction, is the provision of a selection of portions at different heights above the seat of the swing for use by children of different ages. The looped pedal bar 48 also provides a choice of differently spaced supports for the feet.

Though there has been shown a particular embodiment of this invention, and certain preferred modifications thereof, this application is not limited to this particular embodiment and modifications, but it is desired to include in the scope of this invention the construction, combination and arrangement of parts and portions substantially as set forth in the appended claim.

35 What is claimed as new and desired to be secured by Letters Patent is:

A swing adapted for suspension from an overhead support, comprising a pair of suspending cables, means for pivotally securing the upper 40 ends of these cables to said support, a back rest secured to the lower end of one of said cables, a unitary handle bar and pedal bar member secured to the lower end of the other cable, a substantially horizontal seat terminally and pivotally 45 secured to the lower end of said back rest and to an intermediate portion of said unitary member, said unitary member being constructed of tubular stock and said intermediate portion comprising a web disposed between said handle bar and said 50 pedal bar, said bars comprising closed loops.
